UNITED STATES PATENT OFFICE

KEISHIRO KOBAYASHI, OF TOKYO, JAPAN, ASSIGNOR TO GENERAL ELECTRIC COMPANY,
A CORPORATION OF NEW YORK

FLASH LAMP

Application filed May 9, 1932, Serial No. 610,266, and in Japan May 26, 1931.

My invention relates to flash lamps and more particularly to flash lamps used for photographic purposes. Still more particularly my invention relates to ignition means 5 therefor.

Flash lamps are already known in which an oxidizable metal in the form of a ribbon or foil is placed in a transparent bulb filled with oxygen or an oxygen gas mixture. 10 The ignition of the combustible in the known lamps is accomplished by electrically heating up a filament carrying a fulminating substance thereon. This method of ignition requires of course the use of a source of 15 electricity, such as house current or a separate battery. One of the objects of my invention is the provision of means for igniting the combustible which will be simple and will eliminate auxiliary apparatus. 20 Other features and advantages of my invention will appear from the following description of species thereof.

The single figure of the drawing is a view in elevation, with a part of the glass bulb 25 broken away so as to expose its contents.

Referring to the drawing, my invention comprises a glass bulb 10 and a loose filling of a combustible material 11 therein consisting preferably of a thin foil or ribbon of metal 30 such as aluminum or magnesium. The bulb 10 contains a filling of a gas that supports combustion, preferably oxygen or a gas that generates oxygen. A wire 12 of metal having a high heat conductivity such as copper 35 is sealed in one end of the bulb 10 and projects into said bulb and terminates on the outside of the bulb preferably in the form of a spiral. The inward projecting end of the wire 12 carries a highly inflammable substance 13 thereon, such as a mixture of red phosphorus and nitre in equal proportions. 40

In order to flash the lamp heat is applied to the spiral end of the wire 12 as by a match. The heat is conducted through said wire 12 to the inflammable substance 13 which is then ignited and causes the surrounding combustible 11 to ignite instantly. 45

What I claim as new and desire to secure by Letters Patent of the United States is:

50 1. A flash lamp comprising a bulb her-

metically sealed and containing a flashing medium and an ignition means located in said bulb comprising an inflammable substance and a heat conductor in contact therewith extending through said bulb and having a portion thereof extending beyond said bulb. 55

2. A flash lamp comprising a bulb hermetically sealed and containing a metal foil and an ignition means located in said bulb 60 comprising an inflammable substance and a heat conductor in contact therewith extending through said bulb and having a portion thereof extending beyond said bulb. 65

In witness whereof, I have hereunto set my hand. 70

KEISHIRO KOBAYASHI.
